CONTACT STRUCTURE FOR ELECTRIC SWITCHES

Filed May 29, 1925

Inventor.

Talbot T. Greenwood

UNITED STATES PATENT OFFICE.

TALMA T. GREENWOOD, OF EAST TEMPLETON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

CONTACT STRUCTURE FOR ELECTRIC SWITCHES.

Application filed May 29, 1925. Serial No. 33,847.

This invention relates to electric switches of the down-break type and has for an object the provision of means to improve the contact between the separable switch members 5 when they are traversed by a heavy current.

A further object is generally to improve the construction and operation of electric switches.

The figure is a side elevation, partly in 10 section, of the current conducting members of an electric switch embodying the invention.

The magnetic reaction of an electric current traversing a sinuous conductor tends to 15 straighten the conductor. This principle is herein utilized to improve the contact between the stationary and movable switch members under load.

As herein shown, the invention is incorporated in a down-break switch having stationary switch members including fixed conducting studs 10 enclosed in insulating bushings 12. Stationary contact members 14 are fixed to the lower ends of said studs and are 20 provided with lower contact faces 16 which, in accordance with this invention, are inclined downwardly and outwardly.

The movable switch member includes a laminated, or brush, member formed with the 30 intermediate, or body section 18 and the upwardly directed toe-sections 20 which are disposed approximately at right angles with the intermediate section. In accordance with this invention, the toe sections are formed 35 or provided with upper contact faces 22 approximately conformed with the contact faces 16, or inclined downwardly and outwardly. Preferably the toe-sections are adapted to make contact with the fixed contact members 40 approximately in the line of the studs 10. As thus arranged, the magnetic effect of the current traversing the switch tends to force the yielding toe-sections of the brush member outwardly against the downwardly and outwardly inclined contact faces of the fixed 45 contact members, whereby to improve the contact pressure under load.

The laminae of the brush member are adapted to yield in a downward direction under the pressure exerted upon them by the switch mechanism, but the amount of yielding movement is limited by the spacer plate 23 and the limit-plate 24. Said limit plate is provided

with up-turned end-portions 26 which overlie the toe-sections of the brush member and support the toe-sections against undue yielding in an outward direction due to the magnetic reaction of the current traversing the switch. 55

The structure may be otherwise modified 60 without departing from the spirit of the invention.

I claim:

1. An electric switch having a fixed contact member provided with an inclined lower contact face, and a yielding movable switch member comprising a brush member adapted to engage said contact face, the inclination of said contact face and the disposition of the switch members being such as to support said yielding brush member against deleterious lateral displacement due to the magnetic reaction thereon of the current traversing the switch. 65

2. An electric switch having a stud terminated in a fixed contact member provided with an inclined lower contact face, and a yielding movable switch member comprising a brush member having its end portion arranged in line with said stud and adapted to engage said contact face approximately in the line of said stud, said inclined contact face characterized by having an inclination in a direction to support the end portion of the brush member against lateral displacement therefrom due to magnetic forces set up by the current traversing the switch. 70

3. An electric switch having a pair of stationary switch members terminated in fixed contact members provided with downwardly and outwardly inclined contact faces, and a movable switch member including a brush member disposed below said fixed contact members and having upwardly directed toe-sections provided with downwardly and outwardly inclined contact faces arranged to engage the contact faces of said fixed contact members, the inclined contact faces of said fixed contact members characterized by providing abutment faces against which the toe-sections of said brush member are pressed by the magnetic forces acting in said toe-portions. 90

4. An electric switch having a pair of stationary switch members terminated in fixed contact members provided with downwardly 95

and outwardly inclined contact faces, and a movable switch member including a brush member disposed below said fixed contact members and having upwardly-directed toe-sections provided with downwardly and outwardly inclined contact faces arranged to engage the contact faces of said fixed contact members, said toe-sections arranged to engage said fixed contact members approximately in the line of said stationary switch members, the inclined contact faces of said fixed contact members characterized by providing abutment faces against which the toe-sections of said brush member are pressed by the magnetic forces acting in said toe-portions.

5. An electric switch including a pair of stationary switch members terminated in fixed contact members provided with downwardly and outwardly inclined contact faces, and a movable switch member including a brush member disposed beneath said stationary switch members, and comprising an intermediate section and opposed upstanding toe-sections arranged approximately at right angles with said intermediate section, said toe-sections having downwardly and out-

wardly inclined contact faces adapted to engage the contact faces of said fixed contact members approximately in the line of said stationary switch members, the inclined contact faces of said fixed contact members characterized by providing abutment faces against which the toe-sections of said brush member are pressed by the magnetic forces acting in said toe-portions.

6. A contact member for an electric switch including a laminated flexible member having an intermediate horizontal section and opposed vertically extended end-sections terminated in downwardly and outwardly inclined contact faces.

7. A movable switch member for an electric switch including a laminated member having an intermediate horizontal section and opposed and vertically-extended toe-sections arranged approximately at right angles with said intermediate section and provided with downwardly and outwardly inclined contact faces.

In testimony whereof, I have signed my name to this specification.

TALMA T. GREENWOOD.
